CLAIM

The ornamental design for a portable indirect lighting fixture, substantially as shown and described.

DESCRIPTION

FIG. 1 is a perspective view of a portable indirect lighting fixture showing our new design, with the bulb housing portion thereof located in a first position; FIG. 2 is a plan view thereof;

FIG. 3 is a side elevational view thereof;

FIG. 4 is a front elevational view thereof; and

FIG. 5 is another perspective view thereof, showing the bulb housing portion thereof located in a second position.

FIG. 1

FIG. 5

FIG. 2

FIG. 3

FIG. 4
